UNITED STATES PATENT OFFICE.

LEE DE FOREST, OF SPUYTEN DUYVIL, NEW YORK, ASSIGNOR TO DE FOREST RADIO TELEPHONE AND TELEGRAPH COMPANY, OF NEW YORK, N. Y., A CORPORATION OF DELAWARE.

OSCILLATION-GENERATOR.

1,311,264.

Specification of Letters Patent. Patented July 29, 1919.

Application filed September 4, 1915. Serial No. 48,948.

To all whom it may concern:

Be it known that I, LEE DE FOREST, a citizen of the United States, residing at Spuyten Duyvil, in the county of Bronx, State 5 of New York, have made a certain new and useful Invention in Oscillation-Generators, of which the following is a specification.

This invention relates to oscillation generators of the normally oscillating audion 10 type which I will designate oscillions.

The object of the invention is to provide apparatus, circuit arrangements and methods, which are simple and efficient and wherein the oscillation energy generated in 15 the devices of the type referred to is greatly increased, altered or varied.

Other objects of the invention will be more fully hereinafter set forth.

The invention consists substantially in the 20 construction, combination, arrangement and mode of operation, all as will be more fully hereinafter set forth, as shown in the accompanying drawings, and finally pointed out in the appended claims.

25 Referring to the drawings:—

Figures 1 to 10 are circuit diagrams showing various arrangements embodying and for carrying into effect the principles of my invention.

30 Where I mention hereinafter the "oscillation" it will be understood that by such an expression I mean a type of audion shown and described in my co-pending application Serial No. 825,954, filed March 20, 1914, 35 which comprises the usual vessel containing a hot electrode and two cold electrodes, one interposed between the hot electrode and the other, or, in other words, placed at relatively different distances from the hot electrode.

40 I have found that in radio telephone and telegraph transmitter generators of the oscillation type, that is, of the oscillating audion type in which electrode elements are sealed within a closed vessel, the amount of 45 oscillating energy generated may be greatly increased, altered, or varied by impressing, in accordance with the signals to be transmitted, relatively small, slowly changing differences of potential upon electrode elements sealed within the closed vessel. These 50 electrodes upon which the relatively small and slowly changing potentials are impressed may be the same as those employed or concerned in the high frequency generating system, or they may be independent of

the oscillating circuit electrodes, or some may be independent and others the same electrodes employed in the high frequency generation.

In the circuit diagram of Fig. 1 I have 60 shown an oscillation employing a closed vessel 1, which, preferably, is evacuated or exhausted of air, or partially so, with the "wing" or cold plate electrode 2, 2, the filament or hot electrode 5, and the grid electrode 3, 3, sealed therein in the customary manner. In practice the grid electrode is interposed between the plate and filament, though I do not wish to limit myself in this respect. 65

70 Where two wing or plate and two grid electrodes are employed, as in the example shown for illustrative purposes, the best, but not the only permissible arrangement, is to locate a grid element between each plate and the filament. 75

The plate and grid elements or electrodes are connected to the oscillating circuit 21, 11, 10, in the usual way, 21 being the "stopping" condenser, 11, an inductance—in this 80 case the primary winding of an oscillation transformer through which said oscillating circuit is associated with a working circuit, and 10 a condenser, preferably adjustable, in 85 parallel with the inductance. It is to be understood that the oscillating circuit may be associated in any usual and well known manner with the working circuit, the inductive or two-coil transformer coupling being selected as merely illustrative of the principles 90 involved. The working circuit may be of any desired character for utilization of the generated high frequency oscillation. For 95 illustrative purposes I have shown this circuit as a radiating antenna earth circuit containing the aerial 13, the secondary 12 of the transformer or other coupling to the oscillating circuit, and the earth connection, or other counterpoise indicated at 14.

In the arrangement shown wherein a plurality of plate and grid electrodes 2, 3, are employed, the plate electrodes are arranged in parallel in a circuit which includes the positive terminal of a suitable current source 8, preferably, though not necessarily, a direct current generator of from 500 to 1500 volts. This circuit connection also includes the impedance or resistance 9, through which the source 8 delivers its current to the plate electrodes. The negative terminal of the 110

current source is connected to one side of the filament circuit which circuit also contains a current source 6 for heating the filament and a regulating or controlling resistance 7 for controlling the heating current supply to the filament.

In accordance with my invention I propose to control the intensity of the high frequency oscillation energy generated in the 10 apparatus and circuit arrangement above described, by and in accordance with the signals to be transmitted. This result may be accomplished in a variety of ways. In one embodiment of the idea I employ an 15 auxiliary or independent electrode 4, which is also sealed in the vessel 1 and suitably associated with the signal producing element in a circuit the current supply in which is varied according to the signals to 20 be sent. The auxiliary or control electrode may have any suitable or desired location within the vessel 1 and if independent of the oscillation electrodes may bear any desired relation with reference thereto. In the form 25 shown in Fig. 1, where two plate and two grid electrodes are used, I also employ two auxiliary or independent, or what I shall call "control" electrodes, one located between the plate and grid electrodes on one side of 30 the filament and one between the plate and grid electrodes on the other side of the filament. As above stated, however, my invention is not to be limited or restricted to this relation and arrangement. Where the two 35 control electrodes are employed, as shown in Fig. 1, they are connected in parallel to each other in a circuit which includes in series therein the filament 5. This circuit is associated with the signal producing means, 40 shown in this instance, and for illustrative purposes, as a microphone 18. The circuit of the microphone contains the usual battery or other current source 17, and may be associated with the circuit of the control electrode 45 or electrodes in any desired or well known manner. A simple arrangement is shown wherein an inductive coupling is secured through the coils 15 and 16 in said respective circuits. If desired a condenser 50 19 of relatively large capacity is included in the circuit of the control electrodes.

It will be seen that by the arrangement described changes of potential varying in accordance with the signals to be transmitted are impressed upon the auxiliary or control electrodes and the filament, and where the microphone is employed as the signal producing device, the potential variations impressed upon the control electrodes 60 and filament, respectively are voice controlled.

I have discovered that when potential variations are thus impressed upon the elements in the vessel, corresponding but 65 greatly amplified alteration in the ampli-

tudes of the high frequency oscillations generated are produced, and such alterations in amplitudes correspond to the signals to be transmitted, be they produced by sound waves of articulate speech or otherwise. In 70 this way I am enabled to control with relatively small microphone currents and current variations high frequency oscillation energy variations of many hundreds of times the amount represented by the microphone current variations, and in a most simple and efficient manner. 75

In Fig. 2, I have shown a slightly modified arrangement wherein a single plate 2, and a single grid 3 are used, and wherein the 80 control electrode is in the form of two members 4^a, having intermeshing fingers and respectively connected to the terminals of the coil 15. In other respects the circuit connections of the various elements remain the 85 same as above described with reference to Fig. 1.

Another arrangement embodying the principles of my invention is shown in Fig. 3, in which the working circuit is omitted. In 90 this arrangement, however, the control electrodes 4, 4, are located between the grid electrodes 3 and the filament 5. The two control electrodes are respectively connected to the terminals of the coil 15, as in Fig. 2, but the 95 central or neutral point of this coil is connected to one side of the filament circuit. In this manner a positive potential is impressed upon one of the control electrodes 4 at the same time a negative potential is impressed 100 upon the other of said control electrodes, by the operation of the signal producing device, while normally a constant potential is equally impressed upon both of said electrodes, which may be that of one of the 105 terminals of the filament, preferably the negative terminal, or the constant potential normally supplied to both control electrodes may be derived from a battery or other current source indicated at 30. By thus varying the normal potential of the control electrodes in correspondence with the signals to be transmitted, and in conformity with conditions obtaining in the vessel 1, the effectiveness of the amplification of the generated 110 high frequency oscillations is very greatly increased. Thus, where the oscillation is a large one operating energetically under high impressed potentials between the electrodes 2, 2, and 5, it is advantageous to increase the 115 constant potential impressed upon the control electrodes, and this can be accomplished by employing the additional source of potential 30.

In Fig. 4 I have shown another arrangement embodying the principles of my invention wherein is employed what may be termed a double or compound oscillation with independent grid electrodes. In this arrangement a grid 3 is connected through the 120 125

oscillating circuit 21, 11, 10, to the wing or plate 2, but with the grid 3 located within the sphere of influence of the independent plate or wing electrode 2^A, and the filament 5, and preferably between said electrodes 2^A and 5, while the grid 3^A, in like manner, is connected through the oscillating circuit 21^A, 11^A, 10^A, to the plate electrode 2^A, the grid 3^A located within the sphere of influence of plate 2, and filament 5, as, for illustration, between said members. In practice the oscillating circuits 21, 11; 10, and 21^A, 11^A, and 10^A, are ordinarily tuned alike through the condensers 21, and 21^A, and said circuits are respectively associated with the working circuit. This association may be accomplished in any suitable or convenient manner, as, for example, inductively through the windings 12, 12^A, which may be arranged in series in the working circuit, such as the antenna earth circuit 13, 14. A direct current of high voltage is supplied to each plate electrode 2, 2^A, as, for example, from the sources 8, 8^A, through the impedance or choke coils 9, 9^A, the positive terminals of the current sources 8, 8^A, being connected to the plates 2, 2^A. This arrangement of double or compound oscillation I have found in practice to be highly efficient in the generation of high frequency oscillations. While I have shown two independent sources 8, 8^A, of direct current supply for the plates 2, 2^A, independent sources are not essential though preferable. In the operation of the compound oscillation arrangement shown oscillations in one oscillating circuit react from its associated pair of electrodes, through the other pair of electrodes to the oscillating circuit containing the latter, with the result that a more energetic oscillation generation takes place in each oscillating circuit than would be the case if the other circuit is omitted. In other words the presence of one of said oscillating circuits with its associated electrodes in the relation explained increases the generating action of the other oscillating circuit with its association and relation of electrodes, the combined and increased effect of the two sets of oscillations, the circuits being in tune with each other, being obtained in the working circuit.

In Fig. 5 I have shown a slightly modified arrangement of the compound oscillation, but having the same mode of operation. In this arrangement each grid 3, 3^A, is juxtaposed with reference to the plate 2, 2^A, of its own oscillating circuit, and within the influence of its own associated plate and the filament. In this arrangement I have also shown a common source of high voltage direct current 8 for the two plate electrodes 2, 2^A, but with a separate choke coil or impedance in each lead from the common source 8, as indicated at 9, 9^A. The mode of operation of this arrangement is the same as hereinbefore de-

scribed. Oscillations in one oscillating circuit react from one pair of electrodes to the other pair upon the other oscillating circuit, and the combined effect of the two sets of oscillations is obtained in the load circuit 13, 14.

In Fig. 6, I have shown two oscillation generators similar to the one shown in Fig. 1, each containing the auxiliary electrodes 4, 4^A. The wing electrodes 2, 2^A, of these two oscillations are supplied with current, preferably of high voltage and direct current such as from source 8, and their two filaments 5 and 5^A in series with the common heating battery 6, controlled by the common rheostat 7. The two control electrodes 4, 4^A, are connected to a common secondary coil 15, of a transformer of the signal circuit, so that positive potential is impressed on one system while negative potential is impressed on the other. The neutral or center point of the coil 15, may be connected to the common filament lead 36, and a constant potential may be impressed upon each control electrode through a battery 30 if desired, but my invention is not to be limited in this respect.

In Fig. 7, I have shown two oscillations 1 and 1^A, the filaments of which are connected in parallel to a common heating battery 6. The wing and grid electrodes of 1 are connected to the oscillation circuit 10, 11, 21, in the manner hereinbefore described, while the wing and grid electrodes of 1^A are connected to the oscillation circuit 10^A, 11^A, and 21^A, the two coils 11 and 11^A of the respective above named circuits, being inductively associated with a common radiating or load system 13, 14. In this arrangement I propose to employ a high resistance leak path indicated at 41 and 41^A, respectively connecting the grids 3, 3, and 3^A, 3^A, to one of the common filament battery terminals. The grids of each oscillation are connected through choke coils 40 and 40^A, and condensers 42 and 42^A, respectively, to one terminal of the secondary winding of the transformer 15, the primary of which is included in the signal device circuit in the usual manner. The wing electrodes of the two oscillations are supplied through impedance coils 9 and 9^A, with electromotive force from a source of high voltage, such as a direct current generator indicated at 8. When this arrangement is to be used for radio telegraphy, I prefer to insert a signaling key or switch 49 in the common grid lead, and, in this case, to omit the stopping condensers 42 and 42^A, so that the grid electrodes may be given the potential of one leg of the filament, or insulated therefrom in accordance with the telegraphic operation of the key or switch, that is, in accordance with the signals to be sent. I may also introduce a source of electromotive force in the common grid leads referred to, in series

120
125
130

with key 49, so as to impress a larger negative potential upon the grid electrodes. For telegraphing purposes the high voltage source 8 may be an alternating current supply, preferably one of 1000 or 2000 cycles frequency, in which case I obtain for every complete cycle one sustained train of radiated waves during the half cycles in which the potential of the wing or plate electrodes 10 are made positive.

In Fig. 8 is shown an arrangement where in the high frequency energy output of a large oscillation 100, associated inductively or otherwise, as through transformer coils 15 11, 12, with a radiating antenna system 13, 12, 14, is controlled by sound waves which are utilized to generate corresponding undulatory currents which currents are amplified and finally delivered to the oscillation 20 100. In this arrangement a device operated by and in accordance with sound waves, for instance a microphone 18 is included in a circuit containing a current source 17, and associated in suitable manner, as, for example, through the transformers 16, 15, 15^A, 25 with the grid electrodes 3, 3^A, of the audion amplifiers 1, 1^A. The output circuits of the amplifiers which contain the plate and filament electrodes 2, 5, 2^A, 5^A, are in turn, connected to the primary or transformer coils 50, 30 53, respectively. Each of these coils is associated with two independent secondary coils, the secondary coils 51, 52, being associated with coil 50, and the secondary coils 54, 55, being associated with the coil 53. One terminal of each of the secondary coils 51, 52, 54, 55, is connected to the grid or input electrode 73, 83, 73^A, 83^A, respectively, of still larger audion amplifiers 1^B, 1^C, 1^D, 1^E. The plate 40 or output electrodes 72, 82, 72^A, 82^A, of said amplifiers are respectively connected in circuits which include coupling connections 60, 62, 64, 66, current source 8, and one side of the circuits of the associated filaments 75, 45 85, 75^A, 85^A. These filament circuits are supplied with heating current from any convenient source. A current source 6 is shown for the purpose. By this arrangement I am enabled to control very large telephonic currents with an ordinary microphone without danger of burning out or injuring the microphone through excessive current, and with no lag or distortion. The combined effect of these powerful telephonic currents, 50 all of which are in perfect phase relation with each other provided the impedance characteristics of the various audions and circuits connected thereto are made alike, is delivered through secondary couplings 61, 63, 65, 67, connected up in parallel relation, to the common terminals 69, 79, one of which, say terminal 69, is connected to the control electrodes 4 of an oscillation 100. If desired, though not necessarily, a choke coil 55 60 may be included in this connection. The

other terminal 79 may be connected to the filament system of the oscillation 100, as indicated in dotted lines at 57, or it may be connected to earth or other large capacity, as indicated at 58. The oscillation 100 is provided with the usual plate and grid electrodes 92, 93, and filament 95, the circuit of the latter being supplied from current source 96, controlled by rheostat 97, while a source 8 of direct current of high voltage 75 is connected at one terminal through impedance 9 to the plate system, and at the other terminal to one side of the filament circuit. The grid and plate electrodes 93, 92, are connected to the oscillating circuit 80 21, 10, 11, which is associated in the manner before described with the working circuit 13, 12, 14.

By this arrangement I have found it possible to deliver and control very large 85 amounts of energy, or radiated energy if the working circuit is an aerial-earth system, and in perfect consonance with the most delicate variations of the small microphone currents in the original sound-wave controlled circuit.

Instead of combining the magnified telephonic currents from the out-put circuits of the audion amplifiers 1^B, 1^C, 1^D, 1^E, as just described, into one common circuit and using 95 such currents, so combined, to control one oscillation, it is to be understood that the method employed in Fig. 7, may be used. That is to say the out-put circuit of each amplifier 1^B, 1^C, 1^D, 1^E, or any group thereof, 100 may be connected to a separate oscillation and then these separate oscillations coupled up to one common radiating system or circuit. Such an arrangement is shown in Fig. 9 where only the coupling connections 60, 62, 105 64, of the amplifier circuits as described in connection with the arrangement of Fig. 8, or other sources of telephonic currents, are shown. Associated with the couplings 60, 62, 64, are the coupling connections 61, 63, 110 65, one terminal of each of which is led through a telephone condenser 42, 42^A, 42^B, and choke coil 40, 40^A, 40^B, to the grid electrode 3, 3^A, 3^B, of the oscillations 1, 1^A, 1^B, respectively. The other terminals of the connections 61, 63, 65, are connected to the common circuit of the filaments 5, 5^A, 5^B, of the oscillators, which common circuit includes the usual source 6, of heating current and the control resistance 7. I have here shown 120 the wing electrodes 2, 2^A, 2^B, of the oscillators as supplied from a common source 8 of direct current of high voltage, through separate impedances 9, 9^A, 9^B, although it is to be understood that other of the above described 125 arrangements may be employed in this connection.

The output or oscillating circuits 21, 10, 11, 21^A, 10^A, 11^A, 21^B, 10^B, 11^B, of the oscillators are associated, inductively or otherwise, 130

with a common load, working, or radiating circuit. Inductive association is shown as an illustrative arrangement, through the coils 11, 12; 11^A, 12^A; 11^B, 12^B.

5 It will be understood that many other specific arrangements, associations, and connections for accomplishing the objects and purposes above set forth, and for carrying my invention into practical operation, might 10 readily suggest themselves to persons skilled in the art without departure from the spirit and scope of my invention. In its broad scope, therefore, as defined in the claims, I do not wish to be limited or restricted to any 15 particular arrangement shown or described.

But having now set forth the objects and nature of my invention, and various arrangements and methods of carrying the same into practical operation, what I claim 20 as new and useful, and of my own invention, and desire to secure by Letters Patent, is:—

1. A source of electrical oscillating energy including an exhausted vessel containing one hot and three cold electrodes, each of said 25 cold electrodes being located at a relatively different distance from said hot electrode, a work circuit, and means to transmit the generated oscillations to said work circuit comprising circuits associated with said elec- 30 trodes.

2. A source of electrical oscillating energy including an exhausted vessel containing hot and two cold electrodes, a work circuit, and means to transmit the generated oscillations 35 to said work circuit, and a control electrode therefor, each of said cold electrodes and said control electrode being located at a relatively different distance from said hot electrode.

40 3. A source of electrical oscillating energy including an exhausted vessel containing one hot and three cold electrodes, each of said cold electrodes being located at a relatively different distance from said hot electrode, the hot electrode and one cold electrode being electrically connected and the other two cold electrodes being electrically connected together, a work circuit, and means to transmit the generated oscillations to said work 45 circuit comprising circuits associated with said electrodes.

4. A source of electrical oscillating energy including an exhausted vessel containing hot and cold electrodes, and a control electrode 55 therefor, each of said cold electrodes being located at a relatively different distance from said hot electrode, the hot electrode and one cold electrode being connected together and the other cold electrode and said control electrode being connected together, a work 60 circuit, and means to transmit the generated oscillations to said work circuit.

5. A source of electrical oscillating energy 65 including an exhausted vessel containing one hot and three cold electrodes, each of said

cold electrodes being located at a relatively different distance from said hot electrode, and an oscillating circuit connecting two of said electrodes, circuits for the remaining electrodes, a work circuit, and means to transmit the generated oscillations to said work circuit comprising circuits associated with all of said electrodes. 70

6. A source of electrical oscillating energy including an exhausted vessel containing one hot and three cold electrodes, each of said cold electrodes being located at a relatively different distance from said hot electrode, and a signal controlled circuit connecting two of said electrodes, a work circuit, and means for transmitting the generated oscillations to said work circuit comprising circuits associated with all of said electrodes. 75

7. A source of electrical oscillating energy including an exhausted vessel containing one hot and three cold electrodes, each of said cold electrodes being located at a relatively different distance from said hot electrode, an oscillating circuit connecting two of said electrodes and a signal controlled circuit 90 connecting the other two of said electrodes, a work circuit, and means for transmitting the generated oscillations to said work circuit. 95

8. A source of electrical oscillating energy including an exhausted vessel containing hot and cold electrodes and a control electrode therefor, each of said cold electrodes and said control electrode being located at a relatively different distance from said hot electrodes, and a signal controlled circuit connecting said control electrode with said hot electrode, a work circuit, and means for transmitting the generated oscillations to said work circuit comprising circuits associated with all of said electrodes. 100

9. A source of electrical oscillating energy including an exhausted vessel containing hot and cold electrodes, and a control electrode therefor, each of said cold electrodes and said control electrode being located at a relatively different distance from said hot electrode, and an oscillating circuit connecting said cold electrodes, a work circuit, and means for transmitting the generated oscillations to said work circuit comprising circuits associated with all of said electrodes. 110

10. A source of electrical oscillating energy including an exhausted vessel containing a hot and two cold electrodes, a control electrode interposed between said cold electrodes, each of said cold electrodes and said control electrode being located at a relatively different distance from said hot electrode, a work circuit, and means for transmitting the generated oscillations to said work circuit comprising circuits associated with all of said electrodes. 120

11. A source of electrical oscillating energy including an exhausted vessel contain- 125

- ing hot and cold electrodes, each of said cold electrodes being located at a relatively different distance from said hot electrode, and a control electrode therefor, a signal controlled circuit connecting said control electrode and said hot electrode, and an oscillating circuit connecting said cold electrode, a work circuit, and means for transmitting the generated oscillations to said work circuit.
12. An oscillator comprising an exhausted vessel containing a hot electrode and three cold electrodes, each of said cold electrodes being located at a relatively different distance from said hot electrode, an oscillating circuit connecting two of said cold electrodes, and a signal controlled circuit associated with the other of said electrodes, a work circuit, and means to transmit the oscillations generated to said work circuit.
13. An oscillator comprising a hot electrode, two cold electrodes, and a control electrode, each of said cold electrodes and said control electrode being located at a relatively different distance from said hot electrode, an oscillating circuit connecting one of said cold electrodes and said control electrode, and a signal controlled circuit associated with the other of said cold electrodes, a work circuit, and means to transmit the oscillations generated to said work circuit.
14. An oscillator comprising a hot electrode, two cold electrodes, and a control electrode, each of said cold electrodes and said control electrode being located at a relatively different distance from said hot electrode, a series oscillating circuit connecting one of said cold electrodes and said control electrode, and a signal controlled circuit associated with the other of said cold electrodes through a transformer.
15. A plurality of oscillations each including two cold electrodes sealed therein and connected to oscillating circuits, a third cold electrode also sealed within each of said oscillations and connected to a common signaling circuit.
16. A plurality of oscillations each including two cold electrodes sealed therein and connected to oscillating circuits, a third cold electrode also sealed within each of said oscillations and connected to a voice controlled circuit.
17. A plurality of oscillations each including a hot electrode and three separate cold electrodes sealed therein, and a common source of current supply for said hot electrodes, a work circuit, and means for transmitting the generated oscillations to said work circuit comprising circuits associated with said electrodes.
18. A plurality of oscillations each including a hot electrode and three separate cold electrodes sealed therein, and a common

source of current supply for said hot electrodes, each of said cold electrodes being connected to an oscillating circuit, a work circuit, and means for transmitting the generated oscillations to said work circuit comprising circuits associated with said electrodes.

19. A plurality of oscillations each including a hot electrode and a plurality of cold electrodes sealed therein, and a common source of current supply for said hot electrodes, each of said cold electrodes being connected to a series oscillating circuit, and a control electrode separate from the other electrodes of the said oscillation also included in each of said oscillations.

20. A plurality of oscillations, each including a hot electrode and a plurality of cold electrodes sealed therein, and a common source of current supply for said hot electrode, each of said cold electrodes being connected to a series oscillating circuit, and a control electrode separate from the other electrodes of said oscillation also included in each of said oscillations, said control electrodes being connected to a signaling circuit.

21. A plurality of oscillations each including a hot electrode and a plurality of cold electrodes sealed therein, and a common source of current supply for said hot electrodes, each of said cold electrodes being connected to a series oscillating circuit, and an independent control electrode separate from the other electrodes of said oscillation also included in each of said oscillations, said control electrodes being connected to a common signaling circuit.

22. In a radio telephone system, an oscillation comprising an evacuated vessel containing a hot and three or more sets of cold electrodes, a plurality of audion amplifiers associated therewith to control the oscillating energy generated thereby and voice controlled means for controlling said plurality of audion amplifiers.

23. In a radio telephone system, a plurality of audion amplifiers connected in parallel, voice controlled means for controlling said audion amplifiers, and an oscillation comprising an evacuated vessel containing a hot and three or more sets of cold electrodes controlled by each of said audion amplifiers.

24. In a radio telephone system, an oscillation comprising an evacuated vessel containing a hot and three or more sets of cold electrodes, a plurality of audions associated therewith, the output currents of said audions controlling the oscillating energy generated by said oscillation, and sound controlled means for controlling said plurality of audions.

25. In a radio telephone system, a plurality of audions connected in parallel, sound controlled means for controlling the intake circuits of said audions, and an oscillation

- comprising an evacuated vessel containing a hot and three or more sets of cold electrodes controlled by the output circuits of said audions.
- 5 26. In a radio telephone system, a plurality of audions connected in parallel, sound controlled means for controlling the intake circuits of said audions, and an oscillion comprising an evacuated vessel containing 10 a hot and three or more sets of cold electrodes controlled by the output circuit of each of said audions.
- 15 27. In a radio telephone system, an oscillion comprising an evacuated vessel containing a hot and three or more sets of cold electrodes, an audion associated therewith to control the oscillating energy generated thereby, and voice controlled means for controlling said audion.
- 20 28. In a radio telephone system, an oscillion comprising an evacuated vessel containing a hot and three or more sets of cold electrodes, an audion associated therewith, the output circuit of said audion controlling the 25 oscillating energy generated by said oscillion, and sound controlled means for controlling said audion.
- 25 29. In a radio telephone system, an audion, sound controlled means for controlling the intake circuit of said audion, and an oscillion comprising an evacuated vessel containing a hot and three or more sets of cold electrodes controlled by the output circuit of said audion.
- 30 30. In a radio signaling system, an oscillion comprising an evacuated vessel containing a hot and three or more sets of cold electrodes, a plurality of audion amplifiers, associated therewith to control the oscillating energy generated thereby, and signal controlled means for controlling said plurality of audion amplifiers.
- 35 31. In a radio signaling system, a plurality of audion amplifiers connected in parallel, signal controlled means for controlling said audion amplifiers, and an oscillion comprising an evacuated vessel containing a hot and three or more sets of cold electrodes controlled by each of said audion amplifiers.
- 40 50 32. In a radio signaling system, an oscil-
- lion comprising an evacuated vessel containing a hot and three or more sets of cold electrodes, a plurality of audions associated therewith, the out-put currents of said audions controlling the oscillating energy 55 generated by said oscillion, and signal controlled means for controlling said plurality of audions.
33. In a radio signaling system, a plurality of audions connected in parallel, signal 60 controlled means for controlling the intake circuits of said audions, and an oscillion comprising an evacuated vessel containing a hot and three or more sets of cold electrodes controlled by the output circuits of 65 said audions.
34. In a radio signaling system, a plurality of audions connected in parallel, signal controlled means for controlling the intake circuits of said audions, and an oscillion 70 comprising an evacuated vessel containing a hot and three or more sets of cold electrodes controlled by the output circuit of each of said audions.
35. An evacuated vessel containing a filament electrode and a cold electrode, a second cold electrode located between the filament and the first cold electrode, and a third cold electrode located between the filament and the second cold electrode. 75
36. An evacuated vessel containing a filament electrode and a plate electrode, a grid electrode interposed between the filament and the plate electrode, and a second grid electrode interposed between the first grid 80 electrode and the filament.
37. An evacuated vessel containing a filament electrode, a pair of plate electrodes located on opposite sides of said filament electrode, a pair of grid electrodes located on opposite sides of said filament electrode and interposed between the filament and the plate electrode, a second pair of grid electrodes located on opposite sides of said filament electrode and interposed between the 90 first pair of grid electrodes and the filament. 95
- In testimony whereof I have hereunto set my hand this 26th day of August, A. D., 1915.

LEE DE FOREST.
